[57] CLAIM

The ornamental design for a seat cushion, as shown and described.

DESCRIPTION

FIG. 1 is a top rear perspective elevational view of a seat cushion showing my new design;
FIG. 2 is a top plan view thereof;
FIG. 3 is a side elevational view thereof, the side opposite being a mirror of that shown;
FIG. 4 is a bottom plan view thereof;
FIG. 5 is a rear elevational view thereof; and,
FIG. 6 is a front elevational view thereof.
